TOY LOCOMOTIVE

Perry Feuer, Roslyn, N.Y., assignor to Creative Creations, Inc., Hicksville, N.Y.

Filed June 10, 1971, Ser. No. 148,944

Term of patent 14 years

Int. Cl. D21—01

U.S. Cl. D34—15 MM

FIG. 1 is a left side elevational view of a toy locomotive showing my new design.

FIG. 2 is a front elevational view thereof;

FIG. 3 is a right side elevational view thereof;

FIG. 4 is a rear elevational view thereof;

FIG. 5 is a top plan view thereof.

I claim:

The ornamental design for a toy locomotive, as shown.
